United States Patent Office

Des. 209,294
Patented Nov. 21, 1967

209,294

GOLF CLUB

Otis H. Hitt, 511 Middle St., Archbold, Ohio 43502

Filed Jan. 7, 1966, Ser. No. 533

Term of patent 14 years

(Cl. D34—5)

FIG. 1 is a side view showing a golf club embodying my new design;

FIG. 2 is a front view of the golf club shown in FIG. 1; and

FIG. 3 is a plan view of the golf club shown in FIG. 1.

I claim:

The ornamental design for a golf club, as shown.
